(57) **CLAIM**

The design for a support for concrete reinforcing members, as shown and described.

DESCRIPTION

FIG. 1 is a top perspective view of the support for concrete reinforcing members;

FIG. 2 is a bottom perspective view of the support for concrete reinforcing members;

FIG. 3 is a top plan view of the support for concrete reinforcing members;

FIG. 4 is a bottom plan view of the support for concrete reinforcing members;

FIG. 5 is a front side elevation view of the support for concrete reinforcing members;

FIG. 6 is a rear side elevation view of the support for concrete reinforcing members;

FIG. 7 is a right side elevation view of the support for concrete reinforcing members; and,

FIG. 8 is a left side elevation view of the support for concrete reinforcing members.

The broken lines in the drawings are included for the purpose of illustrating unclaimed features and form no part of the claimed design.

1 Claim, 4 Drawing Sheets
